UNITED STATES PATENT OFFICE.

FRANK P. STEIL, OF CUDAHY, WISCONSIN.

STITCH-DOWN SHOE-LASTING MACHINE.

Application filed December 17, 1924. Serial No. 756,516.

The invention relates to stitch-down shoe lasting machines.

The invention relates to that type of lasting machine for stitch-down shoes wherein the out-turned edge of the upper is glued to the adjacent out-sole by the cooperative action of two relatively movable dies, and has for its object to improve upon existing machines of this type by such an arrangement, 10 operation and formation of the dies as will produce a more efficient lasting action on the shoe with an increase in production over known machines.

The invention further consists in the several features hereinafter set forth and more particularly defined by claims at the conclusion hereof.

In the drawings: Fig. 1 is a side elevation view, partly in section, of a machine embodying the invention;

Fig. 2 is a front elevation view thereof;

Fig. 3 is a detail sectional view taken on the line 3—3 of Fig. 2;

Fig. 4 is a detail view showing the action 23 of the dies upon a shoe.

In the drawings the numeral 5 designates the head of the machine, which is usually mounted upon a suitable pedestal 6, and 7 and 8 the cooperative dies.

30 The lower die 7 is preferably a fixed die, that is, it is firmly secured to the head 5, as by mounting its shank portion 9 within an arm 10 on said head and clamping it thereto by a set screw 11.

35 The upper die or shoe-forming tool 8 is preferably the movable die, having its head, preferably of fibre composition, secured to a metal part 8' having a hinge connection with the member 12 through a pivot pin 38, 40 and limited in its swinging movement by cooperative stops 39, 40 and 41, 42 on the forward and rear parts of the hinge and normally held by a spring 43 with the stops 39 and 40 in contact. The

45 member 12 is vertically slidably mounted in a bearing 13 secured to an arm 14 on the head 5, and is prevented from rotating by a square pin 15 mounted in said shank and working in a slot 16 in said bearing 13.

50 The lower die or anvil 7 has an inclined surface 17 upon which the outer sole is laid or held during the lasting operation, by the operator, who stands in front of the machine, and the die 8 has an upwardly curved end portion 18, a relatively flat pressing portion

19 substantially parallel to the surface 17 of the anvil and just back of said end portion, and a recessed or relief portion 20 receding from said end with the result that as the die 8 moves up and down the outturned edge 60 or flange 21 of the upper 22 is firmly pressed against the adjacent outer sole 23, the contacting surfaces of the flange of the upper and the sole edge, or either of these parts, having been coated with cement prior to the 65 lasting operation, so that these parts will stick together, and at the same time, because of the shape of the die 8 and its pivotal mounting, the portion of the upper adjacent the angle between the sole and the last 24 is 70 also shaped to this angle adjacent the beveled edge of the inner sole 25 simultaneously with the drawing over of the upper upon the last 24, and the upper will then be in the desired shaped and stretched position on the last and connected to the outer edge of the sole without requiring the use of staples or other fastening means whereby the subsequent operations of attaching the welt or other parts may be readily performed. Thus, 75 the die 8 has the threefold function of pulling the upper over the last, forming the angle of the upper close to the inner sole and pressing and ironing down the flange upon the adjacent sole, all of which is accomplished by the vertical movement of said die, it being noted that the pressing action of the die upon the flange forms the angle of the upper, and the continued downward pressure upon the lower side thereof draws or 80 stretches the upper over the last. It will be further noted that because of the pivotal mounting used as the die 8 engages the upper it is swung inwardly toward the angle of the last against the pressure of the spring 43 85 until the stops 41 and 42 contact, and that this has a pressing operation on the outturned edge of the upper as well as a pulling down operation on the upper. Furthermore, as the die 8 works from a position above the shoe, 90 it is an easy matter for the operator to observe the work.

The die 8 is preferably power driven and in such a way as to deliver a succession of hammerlike blows upon the upper. To accomplish this a rod 26 secured to the shank of the die extends through a guide 27 on the head 5, and a spring 28 surrounding said rod is interposed between said die and said guide 105 and is adapted to move the die 8 downward- 110

ly through energy stored up in it, and movement of the die 8 being limited by a stop collar 29 having threaded engagement with the upper threaded end of the rod 26 and secured in position by a locknut 30. Washers 31, of leather or other suitable material, are secured beneath the collar 29 to deaden the noise and to relieve the parts of undue shocking strains. For storing up energy in the spring, a rotary shaft 32, driven in any suitable manner from any suitable source of power, is journalled in a bearing in the head 5 and carries a cam 33 which cooperates with a flange 34 on the shank of the die 8, said flange having a recess 35 therein and said cam having an abrupt drop 36 in its profile from its highest point 37 to its low point 37' to permit quick descent after the high point 37 of the cam passes over said collar, with the result that the cam gradually raises the die against the pressure of the spring 28 and then, when the required amount of energy has been stored up in the spring, releases it and causes the die to deliver a hammerlike blow upon the upper, said blows being delivered in relatively quick succession through the continued rotation of the shaft 32.

As a means for connecting the shaft 32 with a source of power, I show a pulley 38, for connection by belt with any power source, loosely mounted on the shaft 32 and having a clutch surface 39 normally held out of engagement with a clutch disk 40, fast on shaft 32, by a spring 41. The pulley 38 is moved into clutched engagement with the disk 40 by a vertically slidable treadle-operated wedge 42, a block engageable with a wedge surface 43 on a collar 44 adjacent the hub of the pulley 38. The wedge 42 is connected to the treadle, not shown, by the rod 45, and when the treadle is depressed by the operator the clutch is engaged and on the release of the treadle the usual spring, not shown, moves the wedge 42 upwardly to permit release of the pulley 38 from the disk 40 by the spring 41. Any other suitable clutch mechanism may be used.

I find that with the above construction the operator can clearly see what he is doing and that the movement of the die or tool 8 with its hammering action causes the upper to be quickly and efficiently shaped to the last and affixed to the outer edge of the sole.

I desire it to be understood that this invention is not to be limited to any particular form or arrangement of parts except in so far as such limitations are included in the claims or necessitated by the prior art.

What I claim as my invention is:

1. In a stitch-down shoe lasting machine, the combination of a supporting anvil and a movable shoe-forming tool, of power driven means actuating said tool to impart successive free hammerlike blows of the tool upon the work whereby to shape the upper to the

last and press the flange of the upper into contact with the outer edge of the adjacent sole.

2. In a stitch-down shoe lasting machine, the combination of a supporting anvil, a movable pressing and forming tool, a spring for moving said tool to its work, and power driven means for intermittently storing up energy in said spring and intermittently releasing it to cause the tool to deliver a succession of free hammer blows upon the work whereby to shape the upper to the last and press the flange of the upper into contact with the outer edge of the adjacent sole.

3. In a stitch-down shoe lasting machine, the combination of a supporting anvil, a movable pressing and forming tool, a spring for moving said tool to its work, and a power driven cam associated with said spring and tool for intermittently storing up energy in said spring and intermittently releasing it to cause the tool to deliver a succession of free hammer blows upon the work whereby to shape the upper to the last and press the flange of the upper into contact with the outer edge of the adjacent sole.

4. In a stitch-down shoe lasting machine, the combination of a supporting anvil, a reciprocating tool-carrying member, a shoe-forming tool hinged to said member for limited swinging movement forwardly and backwardly, spring means for normally holding said tool in its rearward position, and means including a spring for reciprocating said carrying member whereby to cause said tool to engage the flange of the upper and swing forwardly toward the angle of the upper as it presses said flange into contact with the adjacent sole, forms the angle and pulls and shapes the upper over the last.

5. In a stitch-down shoe lasting machine, the combination of a supporting anvil, a reciprocating tool-carrying member, a shoe-forming tool hinged to said member for limited swinging movement toward and away from the work, spring means for normally holding said tool in its rearward position, and means for so reciprocating said carrying members as to produce a succession of free hammer blows of the tool upon the work during which said tool engages the flange of the upper and swings forwardly toward the angle of the upper as it presses said flange into contact with the adjacent sole, forms the angle and pulls and shapes the upper over the last.

6. In a stitch-down shoe lasting machine, the combination of a supporting anvil, a reciprocating tool-carrying member, a pressing and forming tool hinged to said member for limited swinging movement toward and away from the work, spring means for normally holding said tool in its rearward position, a spring for moving said tool to its

work, and a power-driven cam associated with said last-named spring and carrying-member for intermittently storing up and releasing energy in said spring and thus produce a succession of free hammer blows of the tool upon the work during which said tool engages the flange of the upper and

swings forwardly toward the angle of the upper as it presses said flange into contact with the adjacent sole, forms the angle and 10 pulls and shapes the upper over the last.

In testimony whereof, I affix my signature.

FRANK P. STEIL.
